CLAIM

The ornamental design for a speaker cover, as shown and described.

DESCRIPTION

FIG. 1 is a front elevation view of a speaker cover showing the new design;

FIG. 2 is a rear elevation view of the design;

FIG. 3 is a left side elevation view of the design;

FIG. 4 is a right side elevation view of the design;

FIG. 5 is a top elevation view of the design;

FIG. 6 is a bottom elevation view of the design;

FIG. 7 is a front perspective view of the design; and,

FIG. 8 is a rear perspective view of the design.

The broken lines shown in the drawings depict portions of the speaker cover that form no part of the claimed design.
